UNITED STATES PATENT OFFICE.

WILLIAM H. WINNE, OF MERIDIAN, NEW YORK.

SLEIGH.

SPECIFICATION forming part of Letters Patent No. 298,536, dated May 13, 1884.

Application filed March 1, 1884. (No model.)

To all whom it may concern:

Be it known that I, WILLIAM H. WINNE, of Meridian, in the county of Cayuga, in the State of New York, have invented new and useful Improvements in Sleighs, of which the following, taken in connection with the accompanying drawings, is a full, clear, and exact description.

This invention is designed to afford an oscillatory bearing for the body of the sleigh on the supporting-bolster thereof, as represented in the Letters Patent of the United States No. 292,972, granted to me on the 5th day of February, 1884.

My present invention consists in an improvement in the specific construction of the aforesaid device, whereby the same is rendered more stable and durable, and the cost of the manufacture thereof is reduced.

The invention is fully set forth in the annexed drawings, wherein Figure I is a side view of the forward bob-sleigh with the portion of the body supported thereon. Fig. II is an end view of the same. Figs. III, IV, and V are plan views of the bolster, showing my improvement in the various modifications; and Figs. VI and VII are transverse sections, respectively, on lines *x x*, Fig. III, and line *y y*, Fig. V.

Like letters of reference denote like parts in all the figures.

A represents a bob-sleigh of ordinary construction. *C* is a bolster connected with said sleigh by a king-bolt, *a*, and *B* is the body supported on said bolster.

b b are two brackets secured to the under side of the body, and affording the oscillatory bearing for the bolster, said brackets being in this case in the form of metallic straps formed at one end, with an eye in which the end of the bolster is swiveled, so as to allow it to oscillate therein. The means of connecting the bolster with the brackets *b b*, I now form of a metal rod or rods, *r r*, secured to the bolster *C* by clips *e e*, and projecting over the ends of the bolster, as shown in Figs. III, IV, and V, the projecting ends serving as trunnions, which enter the eye of the brackets *b b* and form the oscillatory bearings for the bolster. On heavy

sleighs I prefer to employ a single continuous rod, *r*, as shown in Figs. III and V of the drawings, and provide said rod with a passage for the king-bolt *a*, either in the form of

an eye, *n*, as represented in Fig. III of the drawings, or a curvature of the rod *r* over the end of the king-bolt, as shown in Figs. II and V of the drawings. In order to more firmly secure the rods in their position on the bolster, I countersink them in the top of the bolster, as best seen in Figs. VI and VII of the drawings. At the ends of the bolster I provide the rods with rigid collars *c*, to form an end bearing for the bolster against the side of the bracket *b*.

Having described my improvements, what I claim as new is—

1. In combination with a sleigh-bolster and body supported thereon, brackets interposed between the bolster and body, and a metal rod or rods secured to the bolster and projecting over the ends thereof, and terminating with an oscillatory bearing on the brackets, substantially as set forth.

2. The combination of a sleigh-bolster and body supported thereon, brackets secured to the under side of the body, a continuous metal rod secured to the top of the bolster and having its ends projecting over the ends of the bolster and entering an eye in the bracket, and collars fixed to said rod at the ends of the bolster, substantially as described and shown.

3. In combination with a bolster connected with the sleigh by a king-bolt, and the body supported on said bolster, a continuous metal rod secured to the bolster and provided with an eye for the passage of the king-bolt, and having its ends projecting over the ends of the bolster and entering an eye in the bracket, substantially as described and shown.

4. In combination with the bolster *C* and body *B*, the brackets *b b*, secured to the body, the rod *r*, countersunk in the top of the bolster, and having its end projecting over the end of the bolster and provided with the collar *c*, and the clips *e*, fastening the rod to the bolster, substantially as described and shown.

In testimony whereof I have hereunto signed my name and affixed my seal, in the presence of two attesting witnesses, at Syracuse, in the county of Onondaga, in the State of New York, this 23d day of February, 1884.

WILLIAM H. WINNE. [L. S.]

Witnesses:

C. H. DUELL,
F. H. GIBBS.
